CLAIM

We claim the ornamental design for a luminaire, as shown and described.

DESCRIPTION

FIG. 1 is a perspective view of a luminaire.

FIG. 2 is a front view of the luminaire shown in FIG. 1.

FIG. 3 is a rear view of the luminaire shown in FIG. 1.

FIG. 4 is a right side view of the luminaire shown in FIG. 1.

FIG. 5 is a left side view of the luminaire shown in FIG. 1.

FIG. 6 is a top view of the luminaire shown in FIG. 1.

FIG. 7 is a bottom view of the luminaire shown in FIG. 1.

FIG. 8 is a perspective view of a luminaire.

FIG. 9 is a front view of the luminaire shown in FIG. 8.

FIG. 10 is a rear view of the luminaire shown in FIG. 8.

FIG. 11 is a right side view of the luminaire shown in FIG. 8.

FIG. 12 is a left side view of the luminaire shown in FIG. 8.

FIG. 13 is a top view of the luminaire shown in FIG. 8; and,

FIG. 14 is a bottom view of the luminaire shown in FIG. 8.

The broken lines shown on the drawings having equal length depict portions of the luminaire that form no part of the claimed design. The broken lines of unequal length depict the boundary of the claimed design and form no part of the claimed design.

1 Claim, 8 Drawing Sheets
